(57) **CLAIM**

The ornamental design for a monitoring device, substantially as shown and described.

DESCRIPTION

FIG. 1 is a front perspective view of a monitoring device in accordance with a first embodiment;

FIG. 2 is a rear perspective view of the monitoring device of FIG. 1;

FIG. 3 is a front view of the monitoring device of FIG. 1; FIG. 4 is a rear view of the monitoring device of FIG. 1; FIG. 5 is a left side view of the monitoring device of FIG. 1;

FIG. 6 is a right side view of the monitoring device of FIG. 1;

FIG. 7 is a top view of the monitoring device of FIG. 1; FIG. 8 is a bottom view of the monitoring device of FIG. 1;

FIG. 9 is a front perspective view of a monitoring device in accordance with a second embodiment;

FIG. 10 is a rear perspective view of the monitoring device of FIG. 9;

FIG. 11 is a front view of the monitoring device of FIG. 9; FIG. 12 is a rear view of the monitoring device of FIG. 9; FIG. 13 is a left side view of the monitoring device of FIG. 9;

FIG. 14 is a right side view of the monitoring device of FIG. 9;

FIG. 15 is a top view of the monitoring device of FIG. 9; and,

FIG. 16 is a bottom view of the monitoring device of FIG. 9.

The broken line showing is included for the purpose of illustrating the monitoring device and forms no part of the claimed design.
